DEEP WELL AND CISTERNS AUTOMATIC
PUMPING PLANT

Thaddeus S. Harris, Waverly, Ill.

Application May 29, 1939, Serial No. 276,394

9 Claims. (Cl. 103—2)

My invention relates to a deep well pump of the type in which a high pressure booster jet is used to help lift the water, and has particular reference to means whereby the same pump that supplies well water may also be utilized to automatically supply a cistern water service system.

The control unit here described may be regarded as an improved form of the duplex automatic valve described in my Patent No. 1,606,530 which was issued November 9, 1926.

My present invention also is closely related to the construction described in my application for Patent No. 256,713, filed February 16, 1939, on Deep well pump, and as further described in my application No. 266,314, filed April 6, 1939, patented June 24, 1941, No. 2,246,678. The advantages of the present construction are that it is more compact with the different control units all operated by a single operator element, and that it can be utilized to supply cistern water, or water from some other source as well as from a deep well.

Referring to the accompanying drawings,

Figure 1 shows a diagrammatic illustration of a complete pumping plant with the automatic control unit shown in longitudinal section.

Figure 2 shows a similar sectional view of one end only of the unit when rotated through 90 degrees.

Figure 3 shows a cross section on the line *a*—*b* of Figure 1.

Figure 4 is a diagrammatic view of a complete pumping plant for deep wells only, with the control unit shown in longitudinal section.

Figure 5 is a sectional view of the right end of the control unit of Figure 4, but rotated 90 degrees about its longitudinal axis.

Figure 6 is a diagrammatic view of the complete pumping plant, with a modified form of deep well control unit.

Figure 7 illustrates a sectional view of a control unit that is identical with that of Figure 6 except that a diaphragm operator element is used instead of a plunger.

Referring to Figure 1, a suction type force pump 1 is operated by the motor 2. Motor 2 is controlled by the pressure switch 3 connected to the pump discharge line 6, and also by the switch 3' connected to the tank 7. Switches 3, 3' are connected together in multiple in one of the power feed wires 4. The other feed wire 5 is connected direct to motor 2.

The discharge pipe 6 extends from the discharge chamber of pump 1 to the control unit

port 20. Storage tank 7 is for well water, while tank 8 is for cistern water.

The automatic control unit, which is shown in section, has the intake control chamber 9 and the main discharge control chamber 10 with the supplementary discharge chamber 10'. Cylinder 11' connects chambers 9 and 10 and has the plunger 12 disposed in it. Valve rod 12' is fixed to plunger 12 and extends to the intake and discharge chambers.

The intake chamber 9 is connected to the pump intake by pipe 9'. The well water port 6' provides for connecting chamber 9 to the well 6" by pipe 8', this passage being controlled by valve 11', which is loosely mounted on rod 12'. Sleeve 13 is fixed to rod 12', and a spring 14 is disposed to press valve 11' against it.

Port 15 provides for connecting chamber 9 to the cistern 15' by pipe 15''. Valve 16 controls this passage, being also loosely mounted on rod 12', with spring 16 pressing it against sleeve 13.

Rod 12' extends through packing gland 17, and is fixed to plunger 12, with spring 18 disposed in cylinder 11' against plunger 12. A by-pass passage 19 connects cylinder 11' to the intake chamber 9.

The well water discharge port 21 from chamber 10 is connected by pipe 17' to the tank 7 with the check valve 22 preferably connected into pipe 17'. Valve 23 is fixed to plunger 12 and controls port 21. The jet discharge port 24 has the pipe 25' connecting it to the jet of the booster unit 24''. Valve 25 is fixed to plunger 12 and controls port 24. Port 26 from the supplementary chamber 10' is connected by pipe 27 to tank 8, and is controlled by valve 29. Valve 29 is flexibly mounted, being held open when rod 12' engages it.

The numbering of Figure 1 also applies to Figures 2 and 3.

The operation of the automatic duplex pumping plant as described in Figures 1, 2, and 3 is as follows:

Switches 3, 3' are preferably set to open at about 40 pounds of pressure. Spring 18 is adjusted to break when the pressure differential on plunger 12 becomes about 55 pounds per square inch. The plunger then normally takes the position shown, forcing all valves closed except the cistern intake valve 16 and the discharge valve 29 which remain open. Then if switch 3, because of a drop in pressure in tank 8, closes and starts the pump, water is at first drawn from the cistern and delivered to the cistern water tank 8. Because of the by-pass passage 19 the

pressure under plunger 12 drops to about 5 or 10 pounds of vacuum as soon as the pump starts, the exact pressure varying slightly under different conditions. This release of pressure under plunger 12, which pressure may result from leakage past the plunger, provides that plunger 12 is forced to the left whenever the discharge pressure on its right side becomes about 45 pounds per square inch, supposing there is 10 pounds of vacuum under it. Since switch 3 opens at 40 pounds of pressure it results that when the pressure in tank 8 reaches 40 pounds the pump stops without any movement of the plunger 12, provided switch 3' is open. If switch 3' is also closed then the pump continues to put cistern water into tank 8 until the pressure in the discharge passage reaches 45 pounds, then plunger 12 starts to move to the left. A slight movement opens the jet passage valve 25 putting the jet into operation, while a further movement of the plunger closes valves 29 and 16 and opens valves 23 and 11' to allow the pump to draw well water and deliver it to tank 7, until the opening of switch 3' stops the pump.

In case the pump is at first put into operation by the closing of the well water switch 3' it still draws cistern water at first until the discharge pressure causes the shift as has been described. Means are thus provided whereby the pump can reprime itself from the cistern. This insures that plenty of water can be drawn to refill the well piping in case of any leakage and to also build up the required jet pressure. All the valves controlled by plunger 12 are disposed to operate in a definite sequence, with the well water discharge valve 23 being the last to open, so that a slight movement of plunger 12 to the right practically closes it. In this manner it is provided that, even with the tank pressure at zero, still the discharge pressure will always be maintained sufficient to operate the booster jet.

Referring to Figure 4, the pump 1 has its intake connected directly to the booster unit 24' by pipe 9', into which is connected the check valve 3''. The automatic pressure control and repriming unit 10a has the main discharge chamber 10a which is connected to the pump discharge chamber by port 20 and pipe 6. The jet discharge port 24a is connected to the jet 8'' of the booster unit 24'' by pipe 25' and has the control valve 25. A cylinder 11'' forms an extension of chamber 10a and has the plunger 12 disposed in it, with valve 25 fixed to it. A spring 18 is disposed against plunger 12.

The well water discharge port 21 is connected to tank 7 by pipe 7', and is controlled by valve 23 fixed on plunger 12 by rod 23'. Port 21 has the passage 17 connecting it to the supplementary discharge chamber 10'. Port 26 opens out of chamber 10' and is controlled by valve 29' which is supported between rod 23' and spring 20'. Port 26 is connected by pipe 21' to the intake passage to the pump. Cylinder 11' is connected by pipe 21'' to pipe 21', and thence to the main intake pipe 9'.

The numbering of Figure 4 also applies to Figure 5.

Referring to Figure 6, the pump 1 has the booster unit 24' connected directly to the pump intake by pipe 9''. The pump discharge chamber is connected by pipe 4 to the discharge chamber 10b of the automatic control unit 10b. The chamber 10b has the jet port 24b which is connected to the jet 30 by pipe 25'. Cylinder 31 is

disposed as an extension of discharge chamber 10b and has the plunger 12 which is supported by spring 18. Valve rod 32 is carried by plunger 12, and has fixed to it the valve 25 to control port 24b.

10 A second and main discharge port 21 connects chamber 10b to chamber 33. The valve 23b controls port 21 being supported by spring 34 to lift it when released by link 35. Valve 23b is controlled by the link 35 which is slidably mounted to rod 32, with spring 36 being disposed between it and a stop on rod 32. Chamber 33 has the port 21b by which it is connected to tank 7 by pipe 7'. Another and smaller port 26b connects chamber 33 to a passage 21', which extends to the intake passage to the pump. A valve 29b controls port 26b, being supported by the stem of valve 23b and spring 37. A passage 21'' connects passage 21' to the cylinder 31 back of plunger 12.

20 The booster unit 24' has the jet 30 and has a cylinder 40 connected to the jet passage 25'. The plunger 41 has the cone shaped rod 42, which extends through the jet orifice and the expansion tube 43. A spring 44, supports plunger 41 and a by-pass passage 45 extends from the lower portion of the cylinder 40 to the main intake passage, at a point above the check valve 46.

30 The description of Figure 6 applies also to Figure 7 except that the cylinder 31 and plunger 12 of Figure 6 are replaced by diaphragm chamber 50, and diaphragm 51, with the by-pass 21'' omitted, chamber 35 being open to atmospheric pressure through port 52.

35 The operation of the control and pumping units shown in Figures 6 and 7 is essentially the same as has been described for Figures 4 and 5. The plunger 12 is moved to the right whenever the discharge pressure builds up to a point that overcomes the pressure of spring 18, the space 40 under plunger 12 being relieved of pressure by the by-pass passage 21'' which communicates with pump intake passage 3, by means of passage 21''. As plunger 12 moves to the right, it first opens the jet passage valve 25, allowing water, which is at 45 first drawn from the tank 7, to be delivered to the jet passage, to build up pressure to operate the plunger 41 of the automatic booster jet unit 24. As the jet plunger 41 is moved downward, the tapered control rod 42 is moved to open the jet nozzle, so that the main intake pipe becomes filled and the required boosting effect is developed. As the pressure in chamber 10b of the control unit increases, the lifting of arm 35 allows the main discharge valve 23b to open and the 50 repriming valve 29b to close. The pump is then in full normal operation. Spring 34 must of course be strong enough to open valve 23b against the discharge pressure, while spring 37 is strong enough to close the small valve 29b against tank 55 pressure, while the pump is operating.

60 In the automatic jet unit, the passage 45 from cylinder 40 to pipe 40' prevents leakage which occurs past plunger 41 from escaping directly to the well, yet, in operation, the movement of plunger 41 becomes influenced by the pressure of the surrounding water in the well, being communicated through the passage 45, so that when the water level is low the volume of the jet flow automatically increases to take care of the greater required lift at the low water level.

65 I claim as new:

70 1. In a deep well and cistern automatic pumping plant the combination of a suction type pump, an electric motor operably connected to said pump, a well water storage tank, a cistern

water shortage tank, a well, a cistern, an automatic valve control unit, said unit comprising, a tubular discharge control chamber, an intake valve chamber fixed to said discharge control chamber, a plunger disposed in said control chamber, a spring disposed in that portion of said control chamber that is adjacent to said intake valve chamber to support said plunger, a passage extending from this end of said control chamber to said intake valve chamber, a discharge passage extended from the opposite end of said control chamber to said pump, a delivery passage extended from this end of said control chamber to said well water tank, a second delivery passage from this end of said control chamber, said passage being extended to said cistern water tank, a third delivery passage from this end of said control chamber, said passage being extended downwardly to said well, a control valve in each of said delivery passages, each of said valves being operably connected to said plunger, a passage extending from said intake valve chamber to said pump, a passage extending from said intake valve chamber downwardly to said well, a passage extending from said intake valve chamber to said cistern, a control valve in each of said well and cistern passages, each of said valves being operably connected to said plunger in said control chamber, a booster jet nozzle disposed to discharge upwardly into said well passage, said jet nozzle being connected to said passage that is downwardly extended from said control chamber to said well, a source of electric power comprising two terminal conductors, an automatic pressure controlled switch, said switch being hydrostatically connected to said well water tank, a second pressure controlled switch, said second switch being hydrostatically connected to said discharge passage from said pump to said control chamber, said switches being electrically connected in multiple between one terminal of said motor and one of said terminal conductors, the remaining terminal conductor being connected to the remaining terminal of said motor.

2. In a jet type deep well pump the combination of, a pump, a storage tank, a well, an intake passage extended downwardly from said pump to said well, a booster jet unit in said well, said unit comprising a conical delivery tube with its larger end connected to said intake passage, a jet chamber fixed to said delivery tube, a jet nozzle opening from said chamber and disposed to discharge into the small end of said delivery tube, a cylinder extended from said jet chamber, a plunger disposed in said cylinder, a spring disposed under said plunger, a passage extended downwardly from the small end of said delivery tube, a passage from said cylinder, under said plunger, to said downwardly extended passage, a cone shaped jet control rod extended from said plunger through said jet nozzle, a passage from the top of said jet chamber and extended upwardly to the top of said well, an automatic control unit comprising, a tubular control chamber, a plunger in said chamber, a spring disposed against said plunger on one side of said control chamber, a passage from this side of said control chamber to said intake passage, a discharge passage from said pump to that side of said control chamber opposite to said spring, a main discharge passage from this side of said control chamber to said storage tank, a cone shaped valve in said passage, said valve being operably connected to said plunger, a passage extending from this side of said control chamber to said jet passage which is

upwardly extended from said jet unit, a valve in said passage, said valve being operably connected to said plunger, a passage extending from said tank to said intake passage, a valve controlling said passage, said valve being operably connected to said plunger.

3. The combination of a suction type force pump, a well, an intake passage from said pump to said well, a booster jet unit connected into said passage, a main discharge passage from said pump, a discharge passage from said pump to the jet of said jet booster unit, control valves in each of said passages, a cylinder connected to the discharge chamber of said pump, said cylinder containing a plunger which is operably connected to said discharge control valves, a spring disposed under said plunger, in one portion of said cylinder, and a passage from this portion of said cylinder to said intake passage.

4. In a duplex automatic pumping plant, a duplex automatic valve control unit comprising, a tubular control chamber, an intake valve chamber fixed to said control chamber, a plunger disposed in said control chamber, a centrally disposed port from said intake valve chamber, a port in each end of said intake valve chamber, valves controlling each of said end ports, said valves being operably connected to said plunger, a spring disposed in that portion of said control chamber adjacent to said intake valve chamber to support said plunger, a passage from this portion of said control chamber to said intake valve chamber, a main inlet port into the opposite end of said control chamber, three delivery ports from this end of said control chamber, a control valve in each of said ports, said valves being operably connected to said plunger, and one of said valves being provided with a suitably tapered guide member, said valves being connected to operate in a definite sequence as said plunger moves against said spring.

5. In a jet booster type deep well pumping plant, means for automatically controlling repriming and flow to the jet, said means comprising the combination of a pump, means for operating said pump, a storage reservoir, an intake passage extended downwardly from said pump, a control unit comprising a tubular control chamber, a plunger disposed in said control chamber, a discharge passage extended from said pump to one end of said control chamber, a spring disposed in the opposite end of said control chamber to support said plunger, a passage from this opposite end of said control chamber to said intake passage, a repriming passage extending from said storage reservoir to said intake passage, a valve controlling said passage, said valve being operably connected to said plunger, a main discharge port from that portion of said control chamber which is opposite said spring, a cone shaped valve member controlling said port, said valve member being operably connected to said plunger, a booster jet nozzle disposed to discharge into said intake pipe, a passage connecting said jet nozzle to said discharge passage, a valve in said passage, said valve being connected to said plunger.

6. In a pumping plant means for automatically repriming the pump, said means comprising, a pump, means for operating said pump, a storage reservoir, an intake passage extended downwardly from said pump, a control unit comprising a tubular control chamber, a plunger in said chamber, a discharge passage from said pump to one end of said control chamber, a main discharge port from this end of said control chamber, a

cone shaped valve in said passage, said valve being connected to said plunger, a spring disposed in the opposite end of said control chamber to support said plunger, a passage from this portion of said control chamber to said intake passage, a repriming passage extending from said storage reservoir to said intake passage, a valve controlling said passage, said valve being operably connected to said plunger.

7. In a duplex deep well and cistern automatic pumping plant, a deep well control unit, comprising a tubular control chamber, a plunger disposed in said chamber, a spring disposed in one end of said chamber to support said plunger, a port opening outwardly from this end of said chamber, a port opening into the opposite end of said chamber, also two ports opening outwardly from this end of said chamber, a control valve in each of said two ports, said valves being operably connected to said plunger, a passageway and housing fixed to said chamber, said passageway having an intake and a discharge port, a valve controlling said passageway, said valve being operably connected with said plunger, all of said valves being so disposed as to operate in a definite sequence when the plunger moves.

8. In a pumping plant, means for automatically repriming the pump, said means comprising, a pump, means for operating said pump, a storage reservoir which is at approximately the same horizontal level as said pump, an intake passage

extending downwardly from said pump, a control unit comprising a closed chamber, a movable partition across said chamber, a discharge passage from said pump to one side of said chamber, 5 a main discharge port from this side of said chamber, a valve in said passage, said valve being connected to said movable partition, a spring disposed in the opposite side of said chamber to support said movable partition, a port opening out of this side of said chamber, a repriming passage extending from said storage reservoir to said intake passage, a valve controlling said passage, said valve being operably connected to said movable partition.

9. In a deep well pumping plant, the combination of a suction type force pump, means for operating said pump, a primary discharge passage from said pump, a pressure relief valve in said passage, an intake passage extended downwardly from said pump, a booster jet unit connected into said passage, a secondary discharge passage from said pump to the jet of said booster unit, a cylinder, one end of which opens into said secondary passage at a point near said jet, a plunger in said cylinder, a jet orifice control rod fixed to said plunger and extended to control said jet orifice, a spring disposed in said cylinder against said plunger opposite to said control rod, and a passage from this end of said cylinder to said intake pipe.

THADDEUS S. HARRIS.
